(57) **CLAIM**

The ornamental design of a LED strip light with a spring-clip base, a flexible neck, a USB power port, as substantially shown and described.

DESCRIPTION

FIG. 1 is a front view of the LED strip light of the present invention;

FIG. 2 is a rear view of the LED strip light of the present invention;

FIG. 3 is a front perspective view of the LED strip light of the present invention;

FIG. 4 is a left side view of the LED strip light of the present invention, the right side view being a mirror image thereof;

FIG. 5 is a top view of the LED strip light of the present invention;

FIG. 6 is a bottom view of the LED strip light of the present invention; and,

FIG. 7 is a close-up perspective view of the base of the LED strip light of the present invention with a touch switch and USB power port.
